ALARM MECHANISM.

1,049,303.

Specification of Letters Patent. Patented Dec. 31, 1912.

Application filed April 27, 1912. Serial No. 693,673.

To all whom it may concern:

Be it known that I, CHARLES H. HYDE, a citizen of the United States, residing at Winsted, county of Litchfield, State of Connecticut, have invented certain new and useful Improvements in Alarm Mechanism, of which the following is a full, clear, and exact description.

This invention relates to alarm mechanism for clocks and is designed to combine simplicity of structure with accuracy and reliability of operation.

Broadly stated the invention comprises a spring pressed latch adapted to be moved from locking to unlocking position with reference to the alarm mechanism of the clock, such movement being effected through time controlled means.

I have illustrated in the accompanying drawings a preferable embodiment of my invention in connection with a well known form of clock mechanism.

In the drawings:—Figure 1 is a face view of an alarm clock equipped with the alarm mechanism of my invention, parts being broken away to disclose the application of my device to the alarm mechanism. Fig. 2 is a view in elevation of that part of the clock mechanism provided with the alarm mechanism, certain parts of the frame being shown in section. Fig. 3 is a vertical section on the line 3—3 Fig. 2, part of the framing being broken away to illustrate the alarm escapement.

Referring to the drawings by numerals, 1 indicates the front wall and 2 the rear wall of the casing containing the clock mechanism, 3 the dial face of the clock, and 4 the alarm bell thereof. Mounted in the upper portion of the framing between the front and rear walls 1 and 2 thereof, is a spindle 5 carrying a sleeve 6 fixed thereon. A hammer staff 7 is secured to the sleeve section 6 and extends upwardly therefrom to a point adjacent the bell 4. From this sleeve and extending downwardly therefrom is an arm 7^a forming an extension of the hammer staff and having its end positioned for coöperation with the lock mechanism forming the subject-matter of my invention. The hammer staff is given the usual oscillatory vibrating movement by means of suitable escapement mechanism 8—9 oscillating the spindle 5 and sleeve 6, and suitably driven through a coiled spring 10.

Journalized in the framing 1—2 is an alarm set staff 11 carrying at its outer end beyond the dial face 3 of the clock an indicator arm 12 which coöperates with an alarm dial on the dial face 3 in the usual manner. Rotatably and slidably mounted on the set staff 11 between the front wall 1 of the casing and the front dial face 3 of the clock, is a hub member 13 provided with a gear 14 engaging with the clock hand gearing 65 and properly synchronized therewith. The outer edge of this hub member 13 is provided with a cam edge 15 having a shoulder 15^a formed thereon. Fixed to the set-staff 11 at the outer or cam face of the hub 13 70 is a collar 16 having an arm 16^a extending therefrom and adapted to engage with the outer edge of hub 13. Between the rear face of the hub member 13 and the front wall 1 of the casing, a yoke member 17 is slidably mounted on the set-staff 11, its front face bearing against the hub member 13 and its rear face being engaged by a coiled spring 18 mounted on the set-staff 11 between the yoke 17 and the front wall 1. This coiled spring normally tends to force the yoke 17 and gear carrying hub 13 outwardly against the arm 16^a of the collar 16 which is fixedly secured to the set-staff 11. 75

The yoke 17 is double-armed, one arm 19, 80 which I will term the alarm locking arm, extending inwardly from the yoke through a guiding recess 1^a in the front wall 1 of the frame and being adapted to be positioned in the path of oscillating movement 90 of the hammer arm 7^a to thereby lock the same against bell tapping oscillation. At its opposite end the yoke 17 is provided with a similar and second arm 20 which extends through a guiding aperture 1^b formed 95 in the front wall of the frame and serves to guide and retain the yoke in proper coöperative relation with the alarm mechanism. The yoke being formed with two similar arms, either one of these arms can be used 100 for the alarm lock or the guide arm.

With the foregoing in mind, the operation of the device is as follows: The alarm set-staff 11 is turned by hand to bring its indicator 12 opposite the hour at which it is 105 desired to operate the alarm mechanism, the arm 16^a being parallel with and moving with the indicator. The gear 14, being synchronously geared to the time mechanism, rotates and brings its shouldered portion 15^a 110

- under the arm 16^a at the time at which the indicator 12 has been set, the coiled spring 18 pressing the cam edge 15 against this arm as the hub is rotated by the gear 14 and the yoke 17 with its arms 19 and 20 being pressed inwardly to lock the alarm mechanism against movement. When the shouldered portion 15^a of the cam edge reaches the arm 16^a of collar 16, the coiled spring 18 snaps the yoke 17 and hub member 13 forwardly to bring the low point of the cam edge 15 against the arm 16^a. This withdraws the locking arm 19 from locking engagement with the arm 7^a of the hammer 7 whereupon the alarm mechanism becomes operative and is free to operate the hammer to sound the alarm until either the spring runs down or the continued rotation of gear 14 rides the arm 16^a up over the cam edge 15 of the hub and forces the latter inwardly against the tension of the coiled spring 18 to thereby bring the latch arm 19 of yoke 17 into coöperative engagement with arm 7^a of the alarm hammer.
- 25 While I have described and illustrated my alarm mechanism in connection with a specific form of time controlled actuator and alarm escapement and hammer, I do not desire to be understood as limiting my invention to use with such specific structures but may, on the contrary, modify and adapt the same to various structures within the spirit of my invention and of the appended claims.
- 35 What I claim therefore and desire to secure by Letters Patent is:
1. In a clock, a frame, alarm mechanism carried thereby, an alarm set-staff carried by said frame, a spring actuated yoke mounted on said staff provided with an arm guided in said frame and adapted to be positioned to lock and unlock said alarm mechanism, a time movement carried by said frame, and time-controlled means mounted on said staff and adapted to position said yoke arm in alarm locking and unlocking position.
  2. In a clock, a frame, alarm mechanism carried thereby, an alarm set-staff carried by said frame, a yoke mounted on said set-staff provided with an arm guided in said frame and adapted to be positioned to lock
- and unlock said alarm mechanism, a spring connected to said yoke and tending to move said arm to alarm unlocking position, a time movement carried by said frame, and time-controlled actuating means mounted on said set-staff in coöperative relation with said yoke and adapted to hold said yoke arm in alarm locking position and to be actuated to permit said spring to move said yoke to alarm unlocking position.
3. In a clock, a frame, alarm mechanism carried thereby, an alarm set-staff carried by said frame, a yoke slidably mounted on said set-staff and provided with a pair of arms guided in said frame, one of said arms being adapted to be positioned to lock and unlock said alarm mechanism, a coiled spring mounted on said set-staff and normally tending to move said yoke to alarm unlocking position, and time-controlled means mounted on said set-staff in coöperative relation with said yoke and adapted to retain it in alarm locking position and to be so positioned at a time certain to permit said spring to actuate said yoke arm to alarm unlocking position.
4. In a clock, a frame, alarm mechanism carried thereby, an alarm set-staff carried by said frame, a yoke mounted on said set-staff and having extending from opposite ends thereof a pair of arms guided in said frame and preventing rotary movement of said yoke relative to said set-staff, said arms being adapted to be positioned interchangeably and one of said arms being adapted to be positioned to lock and unlock said alarm mechanism, a coiled spring mounted on said set-staff and normally tending to move said yoke to alarm unlocking position, and time-controlled means mounted on said set-staff in coöperative relation with said yoke and adapted to retain it in alarm locking position and to be so positioned at a time certain to permit said spring to actuate said yoke arm to alarm unlocking position and to return it to alarm locking position.

CHARLES H. HYDE.
